(57) **CLAIM**

The ornamental design for a fixing bracket for drum head, as shown and described.

DESCRIPTION

FIG. 1 is a perspective view of the top, front and right side of a fixing bracket for drum head showing my new design; FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof; and,

FIG. 8 is a view of the fixing bracket for drum head on a reduced scale shown in position on a drum.

The elements shown in broken lines are for illustrative purposes only and do not form any part of the claimed design.
